UNITED STATES PATENT OFFICE.

EDWARD B. NOWOSIELSKI, OF BLOOMFIELD, NEW JERSEY, ASSIGNOR TO SPLITDORF ELECTRICAL COMPANY, OF NEW YORK, N. Y.

ELECTRIC-GENERATOR-OPERATING MEANS.

Application filed August 5, 1922. Serial No. 579,888.

To all whom it may concern:

Be it known that I, EDWARD B. Nowosielski, a citizen of the United States, residing at Bloomfield, in the county of Essex, 5 State of New Jersey, have invented certain new and useful Improvements in Electric-Generator-Operating Means, of which the following is a description, reference being had to the accompanying drawing and to 10 the figures of reference marked thereon.

This invention relates to means for operating an electric generator, particularly of the magneto type that furnishes spark-ing current to the cylinders of an internal 15 combustion engine. In many cases it has been found highly desirable to install a high tension magneto on such engines, but in many cases such installations have been found to be difficult on account of lack of 20 space from the equipment already installed on the engine or chassis carrying the engine.

My invention is particularly adapted for use in connection with an engine of the Ford type. Many electric generator installations 25 have heretofore been proposed for this style of engine, some of which schemes are shown and described in various patents, but all the schemes with which I am familiar are open to some objections. One, and not the least 30 important, is the matter of initial cost, as well as cost of installation.

It is the principal object of my invention to provide means for attaching an igni-tion generator to such an engine and driv-ing the same therefrom, which means will 35 be simple and cheap in its first cost and ex-tremely easy to install.

Other objects will be apparent after a 40 study of this specification and annexed drawings, in which:

Figure 1 shows a longitudinal view of the engine with the electric generator mounted thereon.

Figure 2 is an end view of Fig. 1, but 45 with certain of the parts broken away.

Figure 3 is a view of the mounting bracket used to carry the generator.

Figure 4 is a detailed view of one of the 50 parts shown in Fig. 2.

Figure 5 is a top view of Fig. 4.

Figure 6 is a somewhat enlarged view of the driving means carried on the cam shaft of the engine.

Figure 7 is a side elevation of Figure 6, 55 while

Figure 8 is a view of the electric gen-erator and the member shown in Fig. 4 in an assembled position ready to go on the bracket.

Referring now to the details wherein like 60 members refer to corresponding parts in the various views, 1 illustrates generally the engine complete, having a cooling fan 2, the lower portion of which is broken away in Fig. 2. The bracket 3 has a pair of lugs 65 4 and 5 with attachment points 6 and 7 adapted to receive the engine bolts 8 and 9 in the side of the crankcase. The upper face of the bracket 3 is flat for the reception 70 of the generator frame, which is mounted thereon and held thereto by a strap 10, which terminates in holding down bolts 11 and 12, that pass through notches 13 and 14 respectively in the face of the bracket 3. A slot 15 passes across the face of the 75 bracket 3 substantially at right angles to the line of the generator shaft. Positioned within the slot 15 is a brace 16 having one end slotted at 17 to receive an engine bolt 18. As illustrated in the drawings, engine 80 bolt 18 is used also to hold the fan bracket. The opposite end of the brace 16 is slotted at 19 to receive locking bolt 20. Pins 21 are fastened to the brace 16 and extend upward 85 into base holes in the bottom of the electric generator as shown in Fig. 8.

The generator shaft carries a sprocket wheel 22 suitably fastened thereto. Fastened to the end of the cam shaft of the en-gine is a flange member 23. Positioned on 90 the flange member 23 is a driving sprocket wheel 24, slots 25 being formed therein to receive set screws 26, which are screwed into the flange member 23 and have means 95 for gripping the outer face of the sprocket wheel 24. It will thus be seen that the sprocket wheel may be adjusted angularly with reference to the cam shaft of the en-gine for a purpose which shall be herein-100 after pointed out.

Passing over the two sprocket wheels 22 and 24 is a link chain 27. A casing 28 en-closes the two sprocket wheels and chain and is held in position by a brace 29 passing under the head of the bolt 18 and another brace 30 held by bolt 31 engaging a threaded 105

hole 37 in the side of the bracket 3. It will thus be seen that when it is necessary to take up any stretch in the chain that the strap 10 is loosened by means of the nut on the holding down bolt 11 and loosening the clamping bolt 20 as well as the nut on the bolt 18. The electric generator is then moved or positioned by pushing on the brace 16, which of itself is positioned in the slot 15, so that the generator is moved in a manner that keeps its operating shaft substantially parallel to the cam shaft of the engine. When the proper position has been obtained, the above mentioned bolts are then tightened up.

15 In timing the generator, the set screws 26 are loosened and by a slight pull on the chain of the sprocket, both of the sprockets are moved relative to the cam shaft, thereby shifting the position of the rotating member 20 of the electric generator with respect to the cam shaft. When the proper position has been obtained, the set screws 26 are tightened in position. The guard casing 28 is cut away large enough so as to leave the set 25 screws 26 exposed for the purpose of making the above mentioned adjustment.

An auxiliary pair of braces 32 and 33 are attached to the engine for the purpose of carrying an ignition control rod 34, when an 30 ignition generator is used having an advance lever. On installations of this nature, a fixed spark generator is sometimes used, in which case braces 32 and 33 and rod 34 with lever 35 connecting to the timer lever 36 35 are not required.

This method of driving is such that it can be installed without taking off the radiator from the engine, thereby saving considerable time and work, and does not interfere with 40 the installation of the starting motor or the lighting generator.

While I have shown the clamping belt 20 to cooperate with the slot to hold the outer end of the brace 16 to the bracket 3, this 45 might be omitted as the brace 16 is positioned in the slot 15 beneath the generator and cannot get out of position on account of the engagement of the pins with the base holes of the generator that is securely fastened to the bracket.

Other changes and alterations may be made in the details without departing from the spirit of my invention or the scope of the appended claims.

55 Having thus pointed out the particular details of my invention, what I claim is:

1. Means for operating an electric generator from an engine consisting of; a bracket having arms with points of attachment to said engine, a brace having one end fastened to the engine and the other end to the bracket, devices on the brace for positioning the generator on the bracket, means for holding the generator in engagement 60 with said devices and to the bracket, and

means for driving the generator from the engine.

2. Means for operating an electric generator from an engine consisting of; a bracket having arms with points of attachment to said engine, a brace having one end fastened to the engine and the other end extending in operative relationship to the generator and bracket, devices on the brace for positioning the generator on the bracket, 70 means for holding the generator in engagement with said devices and to the bracket, and means for driving the generator from the engine.

3. Means for operating an electric generator from an engine consisting of; a bracket having arms with points of attachment to said engine, a brace having one end adjustably fastened to the engine and the other end extending in adjustable operative 85 relationship to the generator and bracket, devices on the brace for positioning the generator on the bracket, means for holding the generator in engagement with said devices and to the bracket, and means for driving the generator from the engine.

4. Means for operating an electric generator from an engine consisting of; a bracket having arms with points of attachment to said engine, a slot extending across 95 the face of said bracket, a brace having one end fastened to the engine and the other end lying in said slot, pins carried by the brace for engaging holes in the base of the generator for positioning the same on the 100 bracket, means for holding the generator in engagement with said pins and the bracket, and means for driving the generator from the engine.

5. Means for operating an electric generator from an engine consisting of; a bracket having arms with points of attachment to said engine, a brace having one end fastened to the engine and the other end extending in operative relationship to the generator and bracket, devices on the brace for positioning the generator on the bracket, means for holding the generator in engagement with said devices and to the bracket, a pair 110 of auxiliary braces attached to the engine 115 for supporting a timing lever for the generator, and means for driving the generator from the engine.

6. Means for operating an electric generator from an engine consisting of; a bracket having arms with points of attachment to said engine, a brace having one end fastened to the engine and the other end extending in operative relationship to the generator and bracket, devices on the brace for positioning the generator on the bracket, means for holding the generator in engagement with said devices and to the bracket, a sprocket wheel carried on the cam shaft of 120 the engine, a sprocket wheel on the genera- 125

tor shaft, a link chain connecting said sprockets and a guard over the chain and sprockets.

7. Means for operating an electric generator from an engine consisting of; a bracket having arms with points of attachment to said engine, a brace having one end fastened to the engine and the other end extending in operative relationship to the generator and bracket, devices on the brace for positioning the generator on the bracket, means for holding the generator in engagement with said devices and to the bracket, a flanged member fastened to the engine cam shaft, a sprocket wheel adjustably fastened to said flanged member, a sprocket wheel on the generator shaft and a link belt connecting said sprockets.

8. Means for operating an electric generator from an engine consisting of; a bracket having arms with points of attachment to said engine, a slot extending across the face of said bracket, a brace having one end fastened to the engine and the other end lying in said slot, pins carried by the brace for engaging holes in the base of the generator for positioning the same on the bracket, means for holding the generator in engagement with said pins and the bracket, a sprocket wheel on the generator shaft, a flanged member fastened to the engine cam shaft, a sprocket wheel carried on the flanged member and means cooperating between the flanged member and its sprocket for adjusting the angular relation between the two for the purpose described.

9. Means for operating an electric generator from an engine consisting of; a bracket having two arms with points of attachment to said engines, a slot in said bracket, a brace adjustably fastened at one end to the engine and having its other end lying in said slot and adjustably fastened to the bracket, devices on the brace for positioning the generator on the bracket, means for holding the generator in engagement with said devices and to the bracket, and driving means for the generator including a sprocket wheel on the generator, a sprocket wheel on the cam shaft of the engine and

relatively adjustable thereto, and a link chain connecting the sprocket wheels.

10. In combination, an internal combustion engine, an electric generator for firing fuel in said engine, a mounting bracket for the generator having a flat face for seating the generator and arms with points of attachment to said engine, a slot across the face of said bracket perpendicular to the line of the generator shaft, a brace adjustably fastened at one end to the engine and having its other end lying in said slot below the base of the generator, pins in said brace for engaging holes in the generator frame for positioning the generator on the base, means for holding the generator in position on the pins and to the bracket, a driving sprocket wheel on the engine cam shaft, a driven sprocket wheel on the generator shaft, a chain connecting the two sprockets, and means for adjusting one of said sprockets with respect to the cam shaft.

11. In combination, an internal combustion engine, an electric generator for firing fuel in said engine, a mounting bracket for the generator having a flat face for seating the generator and arms with points of attachment to said engine, a slot across the face of said bracket perpendicular to the line of the generator shaft, a brace adjustably fastened at one end to the engine and having its other end lying in said slot below the base of the generator, pins in said brace for engaging holes in the generator frame for positioning the generator on the base, means for holding the generator in position on the pins and to the bracket, a driving sprocket wheel on the engine cam shaft, a driven sprocket wheel on the generator shaft, a chain connecting the two sprockets, and means for adjusting one of said sprockets with respect to the cam shaft, a guard over the chain and sprockets, said guard being cut away to expose the adjusting means and having a brace attached to the engine and another to the bracket.

In testimony whereof, I affix my signature.

EDWARD B. NOWOSIELSKI.
